UNITED STATES PATENT OFFICE.

OLIVER A. WYCKOFF, OF ASBURY PARK, NEW JERSEY.

BUTTON.

1,206,969.

Specification of Letters Patent.

Patented Dec. 5, 1916.

Application filed February 9, 1916. Serial No. 77,207.

To all whom it may concern:

Be it known that I, OLIVER A. WYCKOFF, a citizen of the United States of America, and a resident of Asbury Park, county of 5 Monmouth, State of New Jersey, have invented certain new and useful Improvements in Buttons, of which the following is a specification.

My invention relates to ornamental buttons, particularly to that type adapted to 10 tons, particularly to that type adapted to be covered by an ornamental fabric, which fabric may be readily removed, replaced or changed to suit the taste of the user.

One object of my invention is to provide 15 a button which is made of separable parts, one of which is attached to the article on which the button is to be used, so that when the parts are separated only a comparatively small part of the button remains attached to 20 the cloth to interfere with laundering.

Another object is to provide means for attaching a covering material to the button, so that the material may be replaced or 25 changed.

Another object is to provide a button comprising a plurality of parts, each of which may be covered with different materials, or which parts may together be covered with a single material. Either or both of the 30

parts may be constructed of an ornamental substance, which may or may not be covered with an ornamental fabric.

Another object is to provide durable and simple means for holding the parts of 35 the button together, which means also draws together the parts to provide for different thicknesses of covering material clamped between the parts. It is understood that this holding means may be applied to a 40 button comprising merely a member for attaching a button to cloth and an ornamental body member.

Other and further objects and advantages will appear from the following description, 45 taken in connection with the accompanying drawings, forming a part of this specification, and will be pointed out in the claims.

In the drawings, in which like reference characters indicate similar parts, Figure 1 50 is a vertical cross-sectional view of a button embodying the preferred form of my invention; Fig. 2 is an underside view of the button shown in Fig. 1, with parts broken away; Fig. 3 is a section through Fig. 1; Fig. 4 is an enlargement of a portion of 55 Fig. 1.

The button herein described for the purpose of disclosing my invention comprises a base member 1, which may be circular or of any desirable form, the lower face of the 60 base member being concave, as shown at 2, and the upper face being provided with a depression 3, which is concentric with the ridge 4 formed in said upper face. A cap member 5, which may have a circular or any 65 other desirable form, is provided in its lower face with a depression 6, which is adapted to accommodate the ridge 4 in the upper face of the base member 1. The lower edge 7 of the cap member 5 may be arranged to 70 fit within the depression 3 of the upper face of the base member 1. The cap member is shown as being covered with covering material 8, which may be of any character, having any color or metallic luster. This 75 covering is stretched over the cap member by means of threads 9. The base member is shown as being provided with a covering 10, which may be of any material, color or metallic luster. Threads 11 may be used to 80 stretch this material across the upper face of the base member, but it is to be understood that they may be dispensed with and threads 12 stretch this material across 85 the lower face thereof.

It will be seen that, when the cap member is positioned upon the base member, the ridge 4, entering the depression 6, and the edge 7, entering the depression 3, will cause the covering materials 8 and 10 to 90 be stretched. To further stretch the material 10 on the base, a back-plate or clamp 13 is provided, which fits partly into the concavity 2 of the base member. This plate 13 is provided with radial slots 14, which 95 give it resiliency.

The loop 15 is provided for attaching the button to the material on which it is desired to use it. This attaching loop has secured to it a shank 16, which extends 100 through the opening in the base member and into the recess 17 in the cap member. The upper end of the shank 16 is screw-threaded at 18, and is also provided with diametrically opposite longitudinal slots 19. 105 Radial openings 20 extend from the periphery of the cap into the recess 17, and, positioned in these openings and held therein, as, for example, by the friction between their outer surfaces and the inner surfaces 110 of the openings 20, are lugs 21, preferably formed of durable material, and extending

into the recess 17. These lugs have width slightly less than the width of the slots 19, so that the shank may be inserted into the recess by translatory longitudinal motion, and, when the shank is rotated, the lugs 21 will engage with the threads thereon and the shank will be locked within the recess 17, and, while the shank is being turned, the three members comprising the 10 button, namely, the back-plate, the base and the cap, will be drawn tightly together. It will be seen that a clamping or locking device is provided which will permit of the use of different thicknesses of covering material, since the shank may be inserted into the recess until all the parts are in contact, and, upon rotation of the shank, whatever threads are opposite the lugs 21 will engage the lugs and the rotation of the shank 15 will cause the parts to be drawn firmly together. The shank can be held against accidental rotation by friction produced by roughening the parts, or in any manner which suggests itself to the person skilled 20 in the art.

The clamping plate is provided with crossed depressions 22, which intersect in the opening through which the shank 16 extends. When the loop 15 is rotated relatively to the back-plate, it will slip into these depressions, due to the resiliency of the plate, and the shank will be held against rotation relatively to the plate. When the shank is rotated so that the lugs are within 30 the slots 19, all parts of the button, except the shank and the loop, can be removed from the material to which the button is attached, so that the button will not interfere with laundrying.

40 Any kind of material may be used to cover the different parts of the button, or both the cap and the base may be covered together, the stitches 12 alone being used, and the material being stretched by the action 45 of the clamping plate 13; or different materials may be used on the cap and base and transparent material placed over both.

While I have illustrated and described, a particular embodiment of my invention, I 50 do not intend that it shall be limited to the specific details herein set forth, but that it shall include various modifications and adaptations which may occur to those skilled in the art, and that it shall be limited 55 only by the hereunto appended claims.

What I claim and desire to secure by Letters Patent of the United States is the following:—

60 1. In a button, the combination of a base member, a cap member, a covering for said cap member, the opposing faces of said members having interfitting parts to stretch said covering when said members are pressed together, and means for holding said members together.

65 2. In a button, the combination of a base member, a cap member, a covering for one of said members, the opposing faces of said members each having a ridge and a depression, the ridge on one member fitting within 70 the depression on the other, whereby said covering is stretched when said members are pressed together, and means for holding said members together.

75 3. In a button, a body member, a back-plate, said body member having a recess therein, and a locking member co-operating with said plate to hold it against the rear face of said body member and adapted to be inserted by longitudinal movement into said 80 recess, the interior of said recess having means to engage said locking member and hold it in said recess.

85 4. In a button, a body member, an attaching member, one of said members having a closed recess and the other a projection, the walls of said recess and said attaching member having projections and depressions to permit the insertion of said projection into said recess by translatory movement and the 90 locking of said parts together upon relative rotation.

95 5. In a button, a body member, an attaching member, one of said members having a recess and the other a projection, said projection and recess being formed to permit the insertion of said projection into said recess by translatory movement and the locking and drawing together of said parts upon 100 relative rotation.

105 6. In a button, a body member, an attaching member, one of said members having a recess and the other a projection, said recess having parts extending from its sides, said projection having portions permitting said 110 projection to be pushed into said recess and engaging said parts upon relative rotation of said member.

115 7. In a button, a base member, a cap member, a back-plate, a covering for said base member and a covering for said cap member, said cap and base members having means on their opposing faces to stretch the covering on said cap member and the covering on one face of said base member when 120 said members are forced together, and said back-plate and the other face of said base member being provided with means to stretch the covering on the other face of said base member when said plate and base member are forced together, and means for holding said members and said plate together.

125 8. In a button, a base member, a cap member, a back-plate, a covering for said base member and a covering for said cap member, said cap and base members having their opposing faces provided with means to stretch the covering on said cap member and the covering on one face of said base member when said members are forced together,

and said back-plate being positioned to hold the covering on the other face of said base member when said plate and base member are held together, and means for forcing 5 said members and plate together and holding them positioned.

9. In a button, a base member, a cap member, a back-plate, a covering for said base member and a covering for said cap member, 10 said cap and base members having means on their opposing faces to stretch the covering on said cap member and the covering on said base member when said members are forced together, and means for holding 15 together said members.

10. In a button, a body member having a recess therein and lugs projecting from the walls of said recess, and an attaching member having a threaded end and longitudinal 20 slots extending across said threads, whereby said attaching member may be thrust into said recess and rotated to lock said members together.

11. In a button, a body member having a recess therein and lugs projecting from the 25 walls of said recess, an attaching member having a threaded end and longitudinal slots extending across said threads, whereby said attaching member may be thrust into said recess and rotated to lock said members together, and means to hold said members in 30 relatively rotated position.

12. In a button, a body member having a recess therein and lugs projecting from the 35 walls of said recess and an attaching member having members thereon, said lugs and said members being arranged to permit said attaching member to be inserted into said recess by substantially translatory motion and to be rotated to engage said lugs with 40 said members to lock said attaching member within said recess.

In testimony whereof, I have signed my name to this specification.

OLIVER A. WYCKOFF.
